(57) **CLAIM**

The ornamental design for an asymmetric handle for a folding multipurpose hand tool, with margin inserts and latch lever, as shown and described.

DESCRIPTION

FIG. 1 is an isometric view from the upper right front of an asymmetric handle for a folding multipurpose hand tool, with margin inserts and latch lever, including our new design, wherein portions of a blade latch mechanism and portions of pivot pins shown in broken line are included merely for illustrative purposes and form no part of the claimed design;

FIG. 2 is a right side elevational view thereof, the left side elevational view being a mirror image of the right side elevational view, wherein the portions of a blade latch mechanism and portions of pivot pins shown in broken line are included merely for illustrative purposes and form no part of the claimed design;

FIG. 3 is a top plan view thereof, wherein the portions of a blade latch mechanism and portions of pivot pins shown in broken line are included merely for illustrative purposes and form no part of the claimed design;

FIG. 4 is a bottom plan view thereof, wherein the portions of pivot pins shown in broken line are included merely for illustrative purposes and form no part of the claimed design;

FIG. 5 is a front end elevational view thereof, wherein the portions of a blade latch mechanism and portions of a pivot pins shown in broken line are included merely for illustrative purposes and form no part of the claimed design; and,

FIG. 6 is a rear end elevational view thereof, wherein the portions of a blade latch mechanism and portions of pivot pins shown in broken line are included merely for illustrative purposes and form no part of the claimed design.
